COMBINED TRAY TABLE RACK AND SERVING TABLE

Edward Klein, Wilmette, Ill., assignor to Quaker Stretcher Company, Kenosha, Wis., a corporation of Wisconsin

Filed June 30, 1960, Ser. No. 61,160

Term of patent 14 years

(Cl. D33—14)

Fig. 1 is a front elevational view of a tray table rack and serving table showing my new design;

Fig. 2 is a side elevational view;

Fig. 3 is a perspective view thereof showing the device in its upright position as a rack for foldable tray tables; and

Fig. 4 is a perspective view thereof showing the device used as a serving table.

The dominant features of my design reside in the portions shown in full lines on the drawings and are characterized by the inclusion of inclined straight frame members having laterally bent upper end portions providing a handle and additional frame members having upper

and lower end portions bent laterally in opposite directions as shown in the drawings.

I claim:

The ornamental design for a combined tray table rack and serving table as shown and described.
